COVERED TRAY FOR FOOD PRODUCTS OR THE LIKE

Dennis John Kossnar, West Chicago, Ill., assignor to Container Corporation of America, Chicago, Ill., a corporation of Delaware

Filed Dec. 30, 1964, Ser. No. 83,232

Term of patent 14 years

(Cl. D58—13)

The figure is a perspective view of a covered tray for food products or the like embodying my new design.

The sides opposite to the sides shown in the drawing are substantially mirror images of the sides shown, while the bottom wall of the covered tray is substantially plain and unornamented.

The essential feature of my invention resides in the cover portion of the tray having chamfered corners, substantially as shown.

I claim:

The ornamental design for a covered tray for food products or the like, substantially as shown and described.
